UNITED STATES PATENT OFFICE.

ALBERT CHORLEY ROGERSON, OF MANCHESTER, ENGLAND, ASSIGNOR OF ONE-HALF
TO ARTHUR FREDERICK HALSTEAD, OF MANCHESTER, ENGLAND.

RIVETING-TOOL.

1,019,088.

Specification of Letters Patent.

Patented Mar. 5, 1912.

Application filed March 10, 1911. Serial No. 613,499.

To all whom it may concern:

Be it known that I, ALBERT CHORLEY ROGERSON, a subject of the King of Great Britain and Ireland, residing at Annandale 5 House, Victoria Park, Manchester, in the county of Lancaster, England, works manager, have invented new and useful Improvements in Riveting-Tools, of which the following is a specification.

10 The invention relates to an improved riveting tool for riveting to a new shape of head the water space stays such as are applied in connection with locomotive fire boxes, boilers, furnaces, &c.

15 The shape of stay head is of a precise form having a comparatively flat top and steep sides, and in which the fibers of the metal are rolled over and assume a curved disposition, while the shaped head is brought very 20 close down on the plate.

The shape of the stay head is got by means of the particular form of tool. It is found that by the use of such a tool as will be hereafter described, not only are the fibers of the 25 metal rolled over and caused to distribute themselves in curved lines as indicated in Figure 1 of the drawings, but the head is caused to bed closely down and all around as regards its annular meeting edge upon the 30 plate as the figure shows, and this close junction enables the stay head to better resist thermal erosion and gives a stay head of much greater strength. Further, the stay head is not cracked around the annular 35 junction edge with the plate which is a common defect with other forms of riveted stay head, because with my improved form of tool, the metal follows the path of least resistance and is gradually rolled over, by the 40 repeated action of the hammer and the tool.

Referring now to the accompanying drawings, Fig. 1 shows in section the precise shape of the stay head or the like, and clearly indicates the curved or arching disposition of the fibers whereby a better stay 45 head results and the metal is brought down close to the plate of the fire-box. Fig. 2 shows in section on a smaller scale the two plates of a locomotive fire-box with a stay, 50 one end of such stay having been riveted to the desired shape by the improved tool. Fig. 3 shows in section the shape of the head when just formed by the tool. Fig. 4 is a longitudinal section of the tool. Fig. 5 is

a face view thereof. Figs. 6 and 7 are similarly a longitudinal section and face view of the tool with a modification.

The improved tool is marked *a* and is forced on or fixed to a shank *b* which is inserted in the neck *c* in connection with the cylinder of a pneumatic hammer or percussive tool of suitable kind. The operative end of the tool is fashioned with three forming or pressing prongs *a'*, *a'*, *a'* set at an angle of 120° to each other, but more than three such prongs may be used. The axis of the tool is bored out to provide a passage *e*. The design of the operative end of the tool and the prongs *a'* is such that the tool will finish the stay head to the desired shape. The stay 70 head is not hemispherical but is nearly flat on the crown and steep at the sides as shown in Figs. 1 and 2. The steepness of the sides at *f* acts as a guide for the pronged tool making it self centering. The operator applies the tool to the projecting head of the stay, the prongs insuring a proper engagement, and during the repeated blows of the pneumatic hammer upon the tool rotates the tool first in one direction and then the other 75 by means of the attached handle *g*. The prongs *a'* form the steep sides of the stay head, and as soon as these sides begin to assume shape they guide the prongs to form the desired shape of head concentric with the 80 axis of the stay. This desired formation of head is assisted as the inner curved part *h* of the tool is forming the dome of the head, by metal of the stay being forced into the hole *e* of the tool, which forms a small pap *i* 85 in the center of the stay head, temporarily blocking up the passage *j* in the end of the stay where such passage is used, as shown in Fig. 3. This pap *i* as it enters the hole *e* in the tool serves to guide the tool in addition 90 to the guiding effect due to the peculiar shape of the stay head, and the pap is afterward cut off, leaving the stay head of the shape shown in Figs. 1 and 2. Any excess of metal after the stay head has been formed 95 may form a fin around the head, which could be cut off by beveling the edges of the prongs *a'*, or the prongs need not be beveled and the fin may be removed by a suitable tool.

The tool as shown in Figs. 4 and 5 may be used for making rivet heads of different shape to that indicated such as hemispherical or conical heads. The inner curved part *h*

of the tool would be shaped to the desired form of head and the central hole *e* would afford a guide for centering the tool.

When forming a head as shown in Fig. 1
5 the steep sides *f* of the stay head serve in themselves to guide the tool when they begin to assume shape so that the provision of further guiding means such as is afforded by the center hole *e* in the tool is not essential to the
10 success of the operation. In Figs. 6 and 7 the tool is shown without such center hole *e*, and the stay head is formed at once in the shape shown in Figs. 1 and 2 without the center pap *i*, and without the necessity of
15 subsequently removing the pap. Otherwise the construction of the tool and the method of using it, to obtain the formation of the desired shape of stay head is the same as already described. The stay referred to may
20 be of copper, brass, steel, iron or other metal or alloy.

I declare that what I claim is—

1. The riveting tool for use with a pneu-

matic hammer or the like, having prongs, formed internally to shape a stay head with a comparatively flat crown and steep sides, a handle to enable the tool to be rotated by hand and a shank to insert in the neck of the cylinder of a pneumatic hammer, substantially as described.

2. The riveting tool for use with a pneumatic hammer or the like having prongs formed to shape a metal head of the desired form, with a central hole into which metal is forced as the head is being formed serving to guide and center the tool, a handle to enable the tool to be rotated by hand and a shank to insert in the cylinder of a pneumatic hammer, substantially as described.

In testimony whereof I have signed my name to this specification in the presence of two subscribing witnesses.

ALBERT CHORLEY ROGERSON.
